UNITED STATES PATENT OFFICE.

ORESTE MOZZALI, OF TREVIGLIO, ITALY.

ELECTRICAL HEATING APPARATUS FOR THE CRUCIBLES OF LINOTYPE COMPOSING MACHINES.

Application filed October 23, 1922, Serial No. 596,346, and in Italy November 3, 1921.

The object of the present invention is an electrical heating apparatus which is especially suitable for the crucibles of linotype composing machines.

The invention is illustrated in the attached drawings in which:

Fig. 1 is a side view of the resistance unit.

Fig. 2 is a plan view of Fig. 1.

Fig. 3 is a section on line 3—3 of Fig. 1.

Fig. 4 is a sectional view, on a larger scale, of the metal protective sheathing of the resistance unit.

Fig. 5 is a cross section of Fig. 4.

Fig. 6 is an exterior view of Fig. 4.

Fig. 7 is a plan view.

Fig. 8 is a section of the end box of the sheathing.

Fig. 9 shows the arrangement of the regulating rheostat.

Fig. 10 shows the rheostat seen from above.

Fig. 11 is a section of Fig. 15 on line 17—17.

Fig. 12 is an elevation of the heater and the rheostat connected together.

The immersible apparatus for the melting of the metal consists of the following (Figs. 1 to 8):

(a) The resistance unit, formed by a wire

1 of high electrical resistance and high working temperature (nickel-chrome alloy), is wound on mica plates, and insulated on both sides by other plates of the same material which are held in place by thin steel

strips 2. The length and the section of the conductors are suitable for the tension and the strength of the current which must pass through the unit. The resistor is in the form of a semi-cylinder, having a lateral ex-

40 tension 3, along which the lead wires 4 and 5 of the heating conductor are carried.

(b) The protective metal sheathing 6 of

45 the resistor, consists of a semi-cylindrical covering of a non-oxidizable sheet steel, having the necessary lateral extension 7. The resistor is inserted therein, and the edges of the latter are then sealed by means of electric welding, thus rendering it completely hermetic. It is then placed under consider-

50 able pressure, so as to ensure the good adherence of its sides to those of the resistor.

At the end of the extension of the sheathing there is a box 9, made from the same sheet

55 steel, in which two terminals 10 are fixed for connecting the ends of the heating conduc-

tor to two insulated copper wires 11 which feed current into the apparatus. An aluminum cover 12 and a flexible metal tube 13 protect the box and the copper wires.

The heat regulating rheostat for the crucible and outlet consists of the following:

(a) A resistor 27 comprises the heating wire, provided with three conductors 28, 29, and 30 which extend along the extension 31 of the resistor together with the ends of the conductor itself. By means of this arrangement it is possible to vary the length of the heating conductor and consequently vary its electrical resistance by connecting it up through its two extremities (maximum resistance), or with one extremity and one of the other three conductors, the latter being connected to the former at different points in its windings.

(b) A sheathing 32, which is hermetically 75 welded together, surrounds the resistor.

(c) An aluminum box 33 which has a hermetically-closed cover, contains the terminals for connecting up five insulated copper conductors of the resistor.

The conductors outside of the box are protected by a flexible metal tube 38.

The size of the above-described regulating rheostat allows it to be placed inside the crucible heating apparatus and to be attached 85 to it by means of two small bolts. By means of controller box handles, said rheostat can be placed in series with the crucible.

I claim as my invention:—

1. An electric heater for crucibles of linotype machines comprising a resistance unit in the form of a semi-cylinder; an extension for said unit; a rheostat in the form of a semi-cylinder; and an extension for said rheostat, said resistance unit and rheostat being adapted to interfit and be secured together by means of said extensions to thus secure them to said crucible.

2. An electric heater for crucibles of linotype machines comprising a semi-cylindrical 100 resistance unit provided with an extension; and a semi-cylindrical rheostat provided with an extension and adapted to fit co-axially inside of said resistance unit, said unit and rheostat being secured together to the 105 crucible by means of the extensions.

3. An electric heater for crucibles of linotype machines comprising a semi-cylindrical resistance unit provided with an extension; a semi-cylindrical rheostat provided with an 110

extension and adapted to fit co-axially with said resistance unit; and a terminal box secured to each extension, said unit and rheostat being secured together and to the crucible by means of the extensions.

4. An electric heater for crucibles of lino-type machines comprising a semi-cylindrical resistance unit; an extension on said unit; a protecting sheathing surrounding 10 said unit and extension; a semi-cylindrical

rheostat; an extension on said rheostat; a protecting sheathing for said rheostat and its extension; and means for co-axially securing the resistance unit and rheostat together by means of said extensions so that 15 said rheostat will act as a heater.

Signed at Milan, Italy, this 6th day of October, 1922.

ORESTE MOZZALI.
